WINDOW FRAME

James D. Blackburn, Drumwright, Okla.

Application May 22, 1939, Serial No. 274,921

6 Claims. (Cl. 20—11)

This invention relates to buildings and particularly that portion of wooden structures adjacent to the glazed window sashes thereof, and the primary object is to provide a window frame 5 which constitutes an integral part of the building framework and which forms a weather and air tight juncture with the wall proper.

One of the important aims of the present invention is the provision of a window frame that 10 is made of relatively heavy planks and which may be pre-fabricated and delivered directly to the job where it is assembled by the workmen as the framework of the building is erected so that no additional parts become necessary when 15 handling the window sash.

This invention has for an even further object 20 the provision of a window frame made of specially formed planks, each of which is arranged to constitute an element of the building framework and to be rigid enough to remain in an accurate place so that when the window sashes are installed, no blocking or time-consuming manipulation is required.

A yet further object of the invention is to 25 provide a window sash frame for buildings, the parts of which not only form an integral portion of the building framework, but are so interlocked as to establish a completely air tight assembly, independent of either the outside or inside casting and trim.

Another important object of this invention is 30 to provide specially formed framework for buildings with which doors or window sashes may be directly and operatively associated and which is made to establish a tight connection with the surrounding wall.

Further objects of this invention are to provide a window frame that will reduce the labor cost of installing; that will permit the contractor to purchase the complete window frame 35 in a knocked-down condition but ready for assembly; that will permit windows to be installed at any time during the construction of the building; that produces a more rigid frame, making 40 setting easier and more accurate; and that eliminates a vast amount of time now ordinarily required to install window frames.

Other objects will appear during the course 50 of the following specification, referring to the accompanying drawings, wherein:

Figure 1 is an outside fragmentary condensed elevational view of a window frame made in accordance with this invention and forming a 55 part of the building framework.

Fig. 2 is an inside fragmentary condensed elevational view of the window frame installed.

Fig. 3 is an enlarged detailed sectional view taken on line III—III of Fig. 1.

Fig. 4 is a similar view taken on line IV—IV 5 of Fig. 1.

Fig. 5 is a like sectional view taken on line V—V of Fig. 1.

Fig. 6 is another enlarged fragmentary sectional view taken on line VI—VI of Fig. 1. 10

Fig. 7 is a sectional view similar to Fig. 6, but illustrating a wider form of mullion.

Fig. 8 is a condensed outside elevational view of a window frame made in accordance with a slightly modified form of the invention, and illustrating a different type of construction. 15

Fig. 9 is a condensed side elevational view of a door frame comprising parts made in accordance with this invention.

Fig. 10 is an enlarged fragmentary sectional 20 view through the door frame taken on line X—X of Fig. 9.

Fig. 11 is a similar view taken on line XI—XI of Fig. 9; and,

Fig. 12 is a condensed fragmentary elevational 25 view of a building framework having door frame parts made in accordance with the modified form of the invention associated therewith.

The framework 10 of buildings with which the window frame embodying this invention is 30 adapted to be associated, includes the conventional, vertical studding 12 and the horizontally disposed plates 14 that are usually lumber in the nature of two-by-fours and upon the outer faces of which is positioned sheeting 16, over which is 35 placed building paper 18 and siding or other surfacing substance 20. The inner side of building framework 10 has lathe 22 and plaster 24 thereon, and during completion of the building, the hereinafter described trim combines with 40 members 16, 18 and 20 on the outside of the building and with members 22 and 24 on the inside of the building to establish the desired appearance.

Since this invention is directed only to the 45 window frame, it will be understood by those skilled in the art that the glazed window sashes 26 are operably mounted, whether through weights, springs, hinges or other equipment. The illustrated embodiment of the invention is 50 devoid of any example of means for movably mounting sashes 26.

The component parts of the window frame 55 per se are made of heavy planks formed in a special manner and milled to interlock at the joints so

that when the carpenter installs the component parts of the frame, only the parts supplied in the kit by the lumber yard, are necessary.

Each window frame comprises a jamb plank 28, the preferred form of which is sectional to present a main section 30 and a pair of completing sections 32. Main section 28 is wider than the two-by-fours from which studding and plates 12 and 14 respectively are made, and since 10 the hereinafter mentioned elements are not needed on completing sections 32, the width of the latter may be the same as the remaining parts of the building framework.

The joint between section 30 and sections 32 15 is preferably in the nature of one having horizontal shoulders 34 so that part of the weight of upper plate 14 may be borne by this jamb plank.

In the illustrated embodiment of the invention a mullion type window has been shown, and 20 where such a window frame is used, mullion plank 36 forms a part of the structure. Head planks 38 equal in width to main section 30 of jamb planks 28 interconnect the latter, or in the case of the mullion type shown, join together mullion 25 plank 36 and jamb planks 28 so as to form the top edge of the opening wherein sashes 26 are disposed. The lower edge of this said opening is bounded by sill plate 40, the cross sectional contour of which is as illustrated in Fig. 5. A 30 bead 42 projects outwardly from the normally lower face of sill plate 40 at the bottom of notch 44 which receives sill plank 46.

The upper face of sill plank 46 has a groove 48 created therein which extends its entire length 35 and bead 42 enters groove 48 when elements 40 and 46 are in the operative position. Sill plate 40 is further rabbeted to present a longitudinal groove 50 at one corner thereof which receives lathe and plaster 22 and 24 respectively.

40 Another longitudinal groove 52 formed in sill plate 40 is for the reception of a marginal edge of siding 20 and the upper inclined face of plate 40 should have shoulder 54 formed thereon in the same plane as sill table 56.

45 When mullion plank 36 is not used to present a pair of openings, sill plate 40 extends completely across the opening to be glazed, but where a mullion window is to be created in the structure, mullion plank 36 extends through sill plate 40 50 and head plank 38 to be joined with members 58 and 46, as seen in Figs. 1, 2 and 8. Any additional blocking necessary to rigidly secure the parts of the window frame to the framework of the building may be introduced and where the 55 mullion plank is employed, vertical blocks 60 and 62 respectively should be interposed to prevent sagging of upper plate 14 when weight is carried thereby, particularly directly over the openings formed by the window frame.

60 Central section 30 of jamb planks 28 have a plurality of longitudinally extending tongues 64 integral with one edge thereof, which edge is the one normally toward the outside of the building. The other longitudinal edge of jamb plank 30 is 65 rabbeted so that a longitudinal groove 67 is formed for the reception of the ends of lathe 22 over which is spread a layer of plaster 24.

67 Head planks 38 likewise have longitudinally extending tongues 66 integral with the normally inner edges thereof, while the opposite longitudinal edges are rabbeted to present groove 68, which serves as regards lathe and plaster 22 and 24 respectively, as does groove 67 of jamb plank 30.

75 The inner faces of jamb planks 30 and head

planks 38 are grooved to receive and operably maintain parting stops 70 in position. These parting stops may be glued, nailed, or otherwise fastened when the parts of the window frame is finished by applying grooved molding 72 directly to tongues 64 of jamb plank 30 and directly to tongues 66 of head plank 38. This molding extends inwardly over the opening outlined by planks 30 and 38 and combine with parting stop 70 in forming a most satisfactory slide-way for 10 the outer window sash 26.

The line of juncture between molding strips 72 and sheeting 16 is approximately midway between the sides of the respective underlying planks 30 and 38, and this joint is in turn covered by finishing strip 74 which extends along the two sides and top of the window frame. The drip cap 76 may be mounted upon the finishing strip 74 along the top of the window frame.

The inside of the window frame is finished 20 through the use of a conventional trim plate 78 that is secured directly to the inner edges of head plank 38 and jamb plank 30. The width of this plate 78 is great enough to overlap the line of connection between members 30 and 38 and the 25 other elements 22 and 24 of the building, and a molding 80 that cooperates with parting stops 70 in producing a slide-way for inner sash 26 overlaps the joint between plate 78 and the inner surfaces of planks 30 and 38.

30 Reference to Figs. 3 and 4 will indicate the manner in which the relatively wide jamb and head planks 30 and 38 respectively, cooperate with the remaining parts just described, to establish a tight head and jamb independent of 35 the casing and trim, that will not permit the passage of air as is the case where pre-formed window frames are set into place and blocked between studding of the building framework.

An extremely narrow mullion is permitted 40 when window frames embodying this invention are introduced into the building walls. The preferred manner of building the mullion is shown in Fig. 6, where mullion plank 36 is grooved along the opposite sides thereof to receive parting stops 45 70 which are of the same nature and form as those introduced into the grooved formed in the aforesaid members 30 and 38. Molding 80 extends upwardly along the inner faces of mullion 50 plank 36 and channel member 82 secured to the outside edge of mullion plank 36 combines with parting stops 70 and said molding 80 in establishing slide-ways for the two sashes 26.

55 Where a wider mullion is desirable, the structure is as shown in Fig. 7. This illustrated embodiment of the invention is shown to indicate the manner in which a mullion type window may have a wider mullion for the purpose of accommodating the various kinds of sash-operating 60 mechanism that are now on the market.

Mullion planks 90 have longitudinal, integral tongues 92 along the outer sides thereof to receive and hold molding strips 94 between which a filler plank 96 is secured. Finishing plate 98 65 (while not necessary to create an air tight structure) is shown to indicate a manner of applying trim which overlaps the joint between elements 94 and 96. The inner side of this wider mullion has a plate 99 that fits into opposed grooves 91 70 in planks 90 to bridge the space therebetween. An ordinary finishing plate 100 cooperates with molding 80 in furnishing a finish.

75 Because of the interlocking relation of sections 30 and 32 of jamb plank 28, head plank 75

38, mullion plank 36, sill plank 46, sill plate 40, sill table 56, molding 72 and parting stops 70—these elements together with member 58 should be pre-formed and packaged for delivery 5 directly to the job. The length of sections 32 may vary because of the distance between plates 14 of the building framework 10. These sections 32 may be somewhat longer than necessary, for it is not fatal to the effectiveness of this rigid 10 window frame structure to have the carpenter cut the ends of sections 32 which abut plates 14 so that a tight fit is insured.

The lower end of mullion plank is slightly reduced in width so that the tongue 37 may extend 15 through notch 41 formed inwardly from the inner edge of sill plate 40. The shoulders created by the production of tongue 37 rest upon the upper face of sill plate 40, while the squared end of mullion plank 36 engages a notch 47 in 20 sill plank 46.

With these aforesaid parts supplied, it is easy for the cabinet maker to finish the window frame both inside and out by using stock materials from which to form trim plates 78, molding 80, 25 finishing strip 74, and finishing plates 98 and 100. The conventional depending apron 84 may also be used on the inside of the window frame immediately below sill table 56.

The modified form of the invention illustrated 30 in Fig. 8, discloses the manner in which jamb planks 101 terminate at the member 102 which is set between studding 12. Head planks 104 engage jamb planks 101 and mullion plank 103 as before set down, and sill plate 108 is identical 35 to the one employed in the preferred embodiment.

One skilled in the art will readily recognize that the concepts of this invention might be embodied in door frame structure, and one illustrated 40 form of door frame, comprising parts formed as contemplated, is shown in Figs. 9, 10 and 11.

In this instance, plate 120 is supported by studding 122 in the normal manner. The head 45 plank 124 is wider than plate and studding 120 and 122 respectively, and extends outwardly to each side thereof to present a portion wherein notch 126 is provided.

As is illustrated in Figs. 3 and 4, the studding 50 has a covering on the inner side, which is made up of lathe and plaster 128 and 130 respectively, while the outer covering constitutes the conventional sheeting 132. The thickness of the inner and outer covering is the same as the depth of 55 notches 126 so that the outer longitudinal edges of head plank 124 lie in the same plane as the outer faces of these coverings. An air tight joint is thereby established, which, while helped by trim plate 134 and finishing strip 136, is not 60 effective without them. The drip cap 138 over-lies strip 136 and siding 140 is usually a part of the structure.

The inner face of head plank 124 has a groove 65 142 therein to receive a relatively wide parting strip 144 against which main door 146 and screen door 148 engage to limit their movement when such doors are hung on the frame. Jamb planks 150 along each side of the opening wherein door 146 is to be hung, is of the same nature as head 70 plank 124 in that it has notches 152 to receive a marginal portion of the inner covering comprising lathes 128 and plaster 130, and the marginal portion of sheeting 132. A dividing strip 154 is pressed into groove 156 which, like groove 75 142, is along the inner face of jamb plank 150.

When installing jamb planks 150 in the manner illustrated in Fig. 9, the main sections thereof are disposed along each side of the opening wherein door 146 is to be placed. End sections 158 are joined to the opposite ends of the main sections to completely fill the distance between upper plate 120 and the lower plate, not here shown. These upper sections 158 combine with main sections 150 in establishing a rigid support in the nature of one of the studdings 122, and 10 when jamb planks 150 are placed in the framework of the building, to reach from plate to plate a connecting member 160 having a width the same as plate and studding 120 and 122 respectively, is employed with an additional short plate 15 162. The blocks 164 are conventional and may be supplied where desired.

In the form of the invention shown in Fig. 12, jamb planks 170 are of the same character with respect to width and grooving, as jamb planks 20 150. Head plank 172 in this form is likewise of the same character as head plank 124. In this instance, jamb planks 170 do not extend to upper plate 120 but terminate against a short plate 174 which joins studding 122 and which is supplemented by a short plate 176.

The nature of the door and window frame elements, with respect to their widths, groovings and relation with inner and outer covering and remaining parts of the building framework, is 30 the same in the door frame as for the window frame installation. Both the door and window frame serves as a support at an integral part of the building framework and permits the establishment of an air tight joint around the window 35 or door frame which needs no calking, covering or other form of weatherproofing.

The parts of a window frame and a door frame, made in accordance with the broad concepts of the present invention, as well as the manner of 40 combining said parts with the framework of a building, have been made clear during the course of the foregoing description, and since structures of a type other than that disclosed might be made without departing from the spirit of the invention, it is desired to be limited only by the scope 45 of the appended claims.

Having thus described the invention, what is claimed as new and desired to be secured by Letters Patent is:

1. A window sash frame for buildings having frame work including vertical and horizontal members constituting studding and plates respectively, comprising a pair of jamb planks supported between the plates; a head plank carried by the 55 jamb planks; and a sill plank, said jamb planks and the head plank being disposed to directly engage the window sash, all of said planks being an integral part of the framework of the building, said plates of the building structure being spaced 60 apart a greater distance than the distance between the head plank and the sill plank, said jamb planks extending beyond the head plank and the sill plank to bridge the space between said plates of the building structure said jamb planks 65 being formed of a plurality of interfitting sections.

2. A window sash frame for buildings having framework including vertical and horizontal members constituting the studding and plates respectively, comprising a pair of jamb planks supported by the jamb planks; and a sill plank, said jamb planks and the head plank being disposed to directly engage the window sash, all of said planks being an integral part of the framework of the 70 75

building, said jamb planks being formed of a plurality of interfitting sections each of said jamb planks having a longitudinal groove formed therein and parting strips positioned in the grooves 5 said jamb planks extending beyond the head plank and the sill plank to bridge the space between said plates of the building framework.

3. A window sash frame for buildings having framework including vertical and horizontal 10 members constituting studding and plates respectively, comprising a pair of jamb planks supported between the plates; a head plank carried by the jamb planks; and a sill plank, said jamb planks and the head plank being disposed to directly 15 engage the window sash, all of said planks being an integral part of the framework of the building, certain of said jamb planks being a plurality of sections joined to provide a plank extending beyond the head planks and said sill plank to bridge 20 the space between the said plates of the building framework.

4. A window sash frame for buildings having framework including vertical and horizontal members constituting studding and plates respectively, comprising a pair of jamb planks supported 25 between the plates; a head plank carried by the jamb planks; and a sill plank, said jamb planks and the head plank being disposed to directly engage the window sash, all of said planks being 30 an integral part of the framework of the building, certain of said jamb planks being a plurality of sections joined to provide a plank extending beyond the head planks and said sill plank to bridge the space between the said plates of the building 35 framework, one section of each jamb plank being wider than the remaining sections thereof and the building framework, said wider section having at least one tongue integral therewith along one longitudinal edge thereof for engaging a molding 40 strip, the opposite longitudinal edge of the said one section being rabbeted to receive other elements of the building.

5. A window sash frame for buildings having framework including vertical and horizontal 45 members constituting studding and plates respectively, comprising a pair of jamb planks supported between the plates; a head plank carried by the jamb planks; and a sill plank, said jamb planks and the head plank being disposed to directly 50 engage the window sash, all of said planks being an integral part of the framework of the

building, certain of said jamb planks being a plurality of sections joined to provide a plank extending beyond the head planks and said sill plank to bridge the space between the said plates of the building framework, one section of each jamb 5 plank being wider than the remaining sections thereof and the building framework, said wider sections having at least one tongue integral therewith along one longitudinal edge thereof for engaging a molding strip, the opposite longitudinal edge of the said one section being rabbeted to receive other elements of the building, said head plank being wider than the building framework, said head plank having at least one tongue integral therewith along one longitudinal edge 10 thereof for engaging a molding strip, the opposite longitudinal edge of said head plank being rabbeted for the purpose specified.

6. A window sash frame for buildings having framework including vertical and horizontal 20 members constituting studding and plates respectively, comprising a pair of jamb planks supported between the plates; a head plank carried by the jamb planks; and a sill plank, said jamb planks and the head plank being disposed to directly 25 engage the window sash, all of said planks being an integral part of the framework of the building, certain of said jamb planks being a plurality of sections joined to provide a plank extending beyond the head planks and said sill plank to 30 bridge the space between the said plates of the building framework, one section of each jamb plank being wider than the remaining sections thereof and the building framework, said wider sections having at least one tongue integral therewith along one longitudinal edge thereof for 35 engaging a molding strip, the opposite longitudinal edge of the said one section being rabbeted to receive other elements of the building, said head plank being wider than the building framework, said head plank having at least one tongue integral therewith along one longitudinal edge 40 thereof for engaging a molding strip, the opposite longitudinal edge of said head plank being rabbeted for the purpose specified, the said opposite longitudinal edges of both the jamb planks and the head plank being in the same plane, said edges having window trim secured thereto and 45 extending over adjacent margins of the other elements of the building.

JAMES D. BLACKBURN.
